(57) **CLAIM**

The ornamental design for a meat probe housing, as shown and described.

DESCRIPTION

FIG. 1 is a top perspective view of a meat probe housing with the cover shown in a closed position, showing my new design;

FIG. 2 is a top view thereof;

FIG. 3 is a bottom view thereof;

FIG. 4. is a right side view thereof;

FIG. 5 is a left side view thereof;

FIG. 6 is a rear view thereof; and,

FIG. 7 is a front view thereof.

The broken lines depict portions of the meat probe housing that form no part of the claimed design.
